US00D772918S

(12) **United States Design Patent** (10) Patent No.: **US D772,918 S**
van den Berg et al. (45) Date of Patent: ** Nov. 29, 2016

(54) **DISPLAY SCREEN OR PORTION THEREOF
WITH GRAPHICAL USER INTERFACE**

(71) Applicant: **Sonos, Inc.**, Santa Barbara, CA (US)

(72) Inventors: **Liesbeth van den Berg**, Medford, MA (US); **Abhishek Kumar**, Santa Barbara, CA (US); **Eduardo Apodaca**, Santa Barbara, CA (US); **Amber Brown**, Santa Barbara, CA (US); **Mark Trammell**, Santa Barbara, CA (US); **Robert Lamourne**, Santa Barbara, CA (US); **Yasser Rashid**, Amsterdam (NL)

(73) Assignee: **Sonos, Inc.**, Santa Barbara, CA (US)

(**) Term: **14 Years**

(21) Appl. No.: **29/484,345**

(22) Filed: **Mar. 7, 2014**

(51) **LOC (10) Cl. 14-04**

(52) **U.S. Cl.**

USPC **D14/487**; D14/489; D14/491

(58) **Field of Classification Search**

USPC D14/485-495

CPC G06F 3/048; G06F 3/04842; G06F

3/04847; G06F 3/0481; G06F 17/211;

G06F 17/212

(57) **CLAIM**

The ornamental design for a display screen or portion thereof with graphical user interface, as shown and described.

DESCRIPTION

The sole FIGURE is a front view of a display screen or portion thereof with graphical user interface showing our new design.

The dash dot broken lines showing a display screen or portion thereof illustrate portions of the article, and form no part of the claimed design.

1 Claim, 1 Drawing Sheet
